UNITED STATES PATENT OFFICE

HUGO BOHL, OF WESTFIELD, NEW JERSEY, ASSIGNOR TO RADIANT LIGHTING FIXTURE CO., INC., OF NEW YORK, N. Y.

DESIGN FOR A GLASS SHADE FOR A LIGHTING FIXTURE OR ARTICLE OF SIMILAR NATURE

Application filed February 12, 1930. Serial No. 34,502. Term of patent 3½ years.

To all whom it may concern:

Be it known that I, HUGO BOHL, a citizen of the United States, residing in Westfield, in the county of Union and State of New Jersey, have invented a new, original, and ornamental Design for a Glass Shade for a Lighting Fixture or Article of Similar Nature, of which the following is a specification, reference being had to the accompanying drawings, forming a part thereof.

Figure 1 is an elevational view of a glass shade showing my new design.

Fig. 2 is a top plan view thereof.

I claim:

The ornamental design for a glass shade for a lighting fixture, or article of similar nature, as shown.

In testimony whereof I affix my signature.

HUGO BOHL
